UNITED STATES PATENT OFFICE.

WILLIAM FRANK BOWER, OF EAST ORANGE, NEW JERSEY.

HEATER FOR GARAGES, &c.

1,180,691.

Specification of Letters Patent. Patented Apr. 25, 1916.

Application filed October 28, 1914. Serial No. 869,028.

To all whom it may concern:

Be it known that I, WILLIAM FRANK BOWER, a citizen of the United States, residing at East Orange, in the county of 5 Essex and State of New Jersey, have invented certain new and useful Improvements in Heaters for Garages, &c.; and I do hereby declare the following to be a full, clear, and exact description of the invention, such as will enable others skilled in 10 the art to which it appertains to make and use the same, reference being had to the accompanying drawings, and to characters of reference marked thereon, which form 15 a part of this specification.

The present invention has reference, generally, to improvements in heating systems; and, the invention relates, more particularly, to a novel means and method for applying heat directly by means of a heater of any suitable construction to a garage or other building in which there is a possibility of the fumes from gasolene, or other explosive gases, coming directly in contact 25 with the fire or flames of the heater.

The present invention, therefore, has for its principal object to provide a direct heating means for garages, or other building, adapted to contain explosive fumes or gases, 30 with a view of locating the heater of any suitable and desirable construction, in a partition or in a wall of the building, so that the various parts of the heater through which the fire or the flames of the heater 35 are exposed are located upon one side of the partition or the wall, and that any possible explosive fumes or explosive gases adapted to be generated upon the other side of the partition or the wall of the building positively can not come in contact with the fire 40 within the heater or with the flames generated by the heater.

The invention has for its further object to provide in combination with a partition 45 or wall for garages and other buildings, a direct heater located within the partition or wall, suitable for burning any fuel, and made gas-tight at the points where the partition or wall is joined to the heater, with a 50 view of providing a cheaper construction of direct heating system, from the ordinary steam-heating or hot water systems, and furthermore providing a system having a more economical consumption of fuel.

The invention has for its further object 55 to provide a direct heating system for garages, etc., for more easily and more economically maintaining the temperature of the building above the freezing point, in cold weather, than can be done with a steam 60 or hot water system; and, furthermore, the invention has for its further object to provide a novel heater, in the form of a furnace or stove, for the purposes above stated and which may be safely used without danger 65 of the explosive fumes sometimes produced in garages, or other explosive gases produced in buildings, coming in contact with the live fire or flames of the furnace or stove.

Other objects of this invention not at 70 this time more particularly enumerated will be clearly understood from the following detailed description of the present invention.

With the various objects of the present invention in view, the invention consists, primarily, of the novel fire or explosion-proof direct heating system for garages and other buildings adapted to contain explosive fumes or explosive gases, herein-after set forth; and, the invention consists, furthermore, in the novel arrangements and combinations of the apparatus, devices and parts, as well as in the construction of the 80 direct heater-apparatus and in the details of the construction of the several parts, all of which will be more fully described in the following specification and then finally embodied in the clauses of the claim which 85 are appended to and which form an essential part of this specification.

While my present invention is applicable for use with garages, and in the accompanying drawings is illustrated in connection with a garage, still it will be clearly evident that the invention is applicable to other buildings which are to be heated, and in which buildings dangerous explosive gases are or may be generated.

In said drawings, Figure 1 represents in horizontal section, the plan of a garage provided with a partition in which is arranged and is illustrated in plan, one form of direct heater, all arranged according to and 105 showing one embodiment of the principles of the present invention. Fig. 2 is a front elevation, on an enlarged scale, of the

heater represented in said Fig. 1, and a fragmentary portion of the partition in which the heater is set. Fig. 3 is a plan or top view of a direct heater and horizontal sectional representation of parts of the outside wall of the building, to illustrate a modified arrangement of the devices and parts, but still embodying the principles of the present invention. Fig. 4 is a transverse vertical sectional representation of the direct heater employed in connection with the parts represented in said Figs. 1 and 2. Fig. 5 is an elevation of a fragmentary portion of a partition or wall and front elevation of a gas-stove or heater arranged with relation to the said partition or wall, in a manner to embody the principles of the present invention; Fig. 6 is a rear view of the heater and partition or wall represented in said Fig. 5; and Fig. 7 is a vertical sectional representation of the wall and side elevation of the gas-stove or heater.

Similar characters of reference are employed in all of the said above described views, to indicate corresponding parts.

Referring now to the figures of the drawings, the reference-character 1 indicates the walls of a suitable room 2, such as a garage, or the like, and 3 indicates a suitable wall or partition, made fume or gas-proof from the main room 2, said partition 3 forming with portions of the main walls 1 a suitable feed-room 4 for the purposes to be presently more fully set forth.

One form of heater, suitable for burning any fuel, is represented in Figs. 1, 2 and 4 of the drawings, the main body 5 of the heater being located directly in the main room 2 where explosive fumes or gases may be generated, said body 5 being constructed with a suitably formed extension, as 6, which is located in, or in relation to the said gas-tight wall or partition 3, that the gases or fumes which may be generated in the room 2 are excluded from the flame, fire, and the combustion chamber and ash-pit of the heater.

That access may be had to the combustion chamber 7 and the ash-pit 8 of the said heater, the front plate 9 of the heater is made with the usual openings 10 and 11 and doors 12 and 13, the said front plate 9 with its openings and doors being located in the feed-room 4 hereinabove mentioned. The said front plate 9 is also provided with a suitable throat, as 14, adapted to receive a smoke-pipe or duct 15 in communication with a chimney, as 16, the said smoke-pipe being located directly within the feed chamber 4, away from the main room 2, so that all danger of explosive fumes or gases entering any possible loose joints in the smoke-pipe and coming in contact with the flames or fire within the stove or heater is obviously avoided, as will be clearly evident.

In order that a fuel or gas-tight joint may be had between the partition or wall 3 and the heater, the latter is provided with a flange-like element, as 17, which forms with the back of the front plate 9, a suitable receiving space 18 into which the partition or wall is fitted and is made tight in any suitable manner.

In lieu of fitting the heater in an inside partition or wall in a manner as set forth hereinabove, the heater may be placed directly in one of the main walls 1 of the building, substantially as illustrated in Fig. 3 of the drawings. In this case, the heater is provided with a pair of flange-like elements 19 and 20, forming a receiving space, as 21, into which the main wall 1 is fitted and made gas-tight, the means of access to the interior of the heater being located upon the outside of the building. The heater-body in this case is also provided at or near its front with a suitably disposed throat, as 22, for the reception of a suitable smoke-pipe which is thus located upon the outside of the building, as will be clearly evident from an inspection of said Fig. 3 of the drawings.

If desired, instead of a heater of the general character hereinabove described, a liquid fuel burner or gas-heater may be employed. One form of such heater is illustrated in Figs. 5, 6 and 7 in connection with the wall 1 of the building.

The heater here shown is in the form of a suitably constructed gas-stove, the same comprising a burner-containing chamber, as 23, provided with a front 24 and a pair of flanges 25. In said front is the usual opening over which is hinged a suitably constructed door, as 26, for ventilation of the chamber 23, and for ignition of the fuel at the burner within said chamber. Upon that side of the wall 1 where dangerous fumes or explosive gases are adapted to be produced, the burner-chamber 23 is provided with a plurality of heater-tubes 27, the upper end-portions of which extend in forward directions, as at 28, and terminate in an exhaust-chamber, as 29, said chamber 29 having an exhaust-opening, as 30, which is located upon the outer side of the wall 1.

The box forming the said exhaust chamber 29 is also provided with flange-like elements 31 in alignment with the flanges 25, said flanges 25 and 31 forming suitable receiving spaces into which portions of the wall or partition are suitably secured in a gas-tight manner, as will be clearly understood more particularly from an inspection of said Fig. 7 of the drawings.

From the foregoing description it will be clearly seen, that I have provided a simple, cheap and most economical heating system which consists in locating a heater of any

suitable and desirable construction, and for
burning coal, wood, gas, oil, or any suitable
or desirable fuel, in, or in such relation to,
or in combination with an interior wall or
5 partition or an outside wall of a building
in which explosive fumes or explosive gases
are or are adapted to be produced, so that
the various parts of a heater through which
the fire or flames are exposed are located on
10 the side of the dividing wall or partition
or the outside wall opposite to the side of
such partition or wall where such explosive
fumes or gases are or might be generated,
while the part of the heater utilized for
15 heating is located directly in the room to be
heated, and hence the ignition of such ex-
plosive fumes or gases which might be gen-
erated in the room is entirely overcome.

Of course I am fully aware that changes
20 may be made in the arrangements and com-
binations of the various devices and parts,
as well as in the details of the construction
of the said devices and parts, without de-
parting from the scope of the invention set
25 forth in the foregoing specification and as
defined in the clauses of the claims which are
 appended to and which form an essential
part of the said specification. Hence, I do
not limit my present invention to the exact
30 arrangements and combinations of the sev-
eral devices and parts as described in the
said specification, nor do I confine myself
to the exact details of the construction of
the said parts as illustrated in the accom-
35 panying drawings.

I claim:—

1. In a garage, comprising a pair of com-
partments, in one compartment of which ex-
plosive fumes or explosive gases may be
40 generated, a gas-tight partition devoid of
openings separating the compartment in
which the explosive fumes or gases are
adapted to be generated from the other
compartment, and a heater located in said
45 gas-tight partition and sealed with relation
thereto, so that all outlets or openings of
the heater through which explosive fumes or
gases might enter are located on one side
of the gas-tight partition, and that the ex-
50 plosive fumes or gases that may be generated
upon the other side of the gas-tight partition
will be excluded from access to the flames or
fire within the heater.

2. In a garage, comprising a pair of com-
partments, in one compartment of which ex-
plosive fumes or explosive gases may be gen-
erated, a gas-tight partition devoid of open-
ings separating the compartment in which
60 the explosive fumes or gases are adapted to
be generated from the other compartment, a
heater located in said gas-tight partition,
and flange-like elements extending from said
heater on opposite sides with said gas-tight
65 partition and sealed therewith, so that all
outlets or openings of the heater through

which explosive fumes or gases might enter
are located on one side of the gas-tight par-
tition, and that the explosive fumes or gases
that may be generated upon the other side
of the gas-tight partition will be excluded 70
from access to the flames or the fire within
the heater.

3. In a garage, comprising a pair of com-
partments, in one compartment of which ex-
plosive fumes or explosive gases may be 75
generated, a gas-tight partition devoid of
openings separating the compartment in
which the explosive fumes or gases are
adapted to be generated from the other
compartment, and a heater comprising a 80
main heater-body provided with a fuel-re-
ceiving chamber located in said gas-tight par-
tition, and extending into the compartment
in which the explosive fumes or explosive
gases are adapted to be generated, and a 85
front-plate connected with said heater-body
and located upon that side of the gas-tight
partition away from contact with the explo-
sive fumes or explosive gases that may be
generated upon the other side of said gas- 90
tight partition, said heater-body and said
front-plate being sealed with relation to said
gas-tight partition, said front plate having
openings therein, and doors placed over said
openings, all arranged so that all outlets or 95
openings of the heater through which ex-
plosive fumes or gases might enter are lo-
cated on one side of the gas-tight partition,
and that the explosive fumes or gases that
may be generated upon the other side of the 100
gas-tight partition will be excluded from
access to the flames or the fire within the
heater.

4. In a garage, comprising a pair of com-
partments, in one compartment of which ex-
plosive fumes or explosive gases may be 105
generated, a gas-tight partition devoid of
openings separating the compartment in
which the explosive fumes or gases are
adapted to be generated from the other com-
partment, and a heater comprising a main 110
heater-body provided with a fuel-receiving
chamber located in said gas-tight partition,
and extending into the compartment in
which the explosive fumes or explosive gases
are adapted to be generated, and a front-plate 115
connected with said heater-body and located
upon that side of the gas-tight partition
away from contact with the explosive fumes
or explosive gases that may be generated
upon the other side of said gas-tight parti- 120
tion, said heater-body and said front plate
being sealed with relation to said gas-tight
partition, said front plate having openings
therein, doors placed over said openings, a 125
smoke-pipe throat extending from said front
plate, and a smoke-pipe connected with said
throat, all arranged so that all outlets or
openings of the heater through which ex-
plosive fumes or gases might enter are lo- 130

cated on one side of the gas-tight partition, and that the explosive fumes or gases that may be generated upon the other side of the gas-tight partition will be excluded from access to the flames or the fire within the heater.

In testimony, that I claim the invention

set forth above I have hereunto set my hand this 26th day of October, 1914.

WILLIAM FRANK BOWER.
